UNITED STATES PATENT OFFICE.

EBENEZER S. WATERMAN, OF WALLA WALLA, WASHINGTON.

CHANGEABLE-SPEED MECHANISM.

1,269,985.

Specification of Letters Patent. Patented June 18, 1918.

Application filed May 12, 1917. Serial No. 168,192.

To all whom it may concern:

Be it known that I, EBENEZER S. WATERMAN, a citizen of the United States, residing at Walla Walla, in the county of Walla 5 Walla and State of Washington, have invented certain new and useful Improvements in Changeable-Speed Mechanism, of which the following is a specification.

This invention relates to a changeable speed device, and has for its principal object to provide a simple, strong, and portable mechanism adapted for various uses but designed primarily to be employed on a farm for transmitting the power of a motor to any 10 and all classes of farm machinery, such as fanning mills, corn shellers, pumps, washing machines, etc., and for changing or adjusting the power or speed of the motor to suit the particular machine being driven. The 15 mechanism about to be described comprises few parts, is convenient, portable and also readily operable for changing the power and speed of the motor, and for reversing the direction of rotation, and also for changing 20 the speed of such reversed movement. By the use of this mechanism it is possible to transmit the rotary movement of a motor that runs at constant speed to any machine to be driven and quickly adjust the speed of 25 the motor to suit said machine without resorting to the shifting of belts, changing pulleys, or taking other trouble that is usual when a change of speed is found to be necessary.

With the above as the principal objects in view, the invention consists in the novel construction, combination, and arrangement of parts hereinafter described, pointed out in the appended claim, and illustrated in the 30 accompanying drawings, in which—

Figure 1 is a top plan view of the improved machine for changing and reversing speed from a prime mover,

Fig. 2 is front elevation of the same,

Fig. 3 is a detail sectional view on the line 3—3 of Fig. 1,

Fig. 4 is a detail sectional view on the line 4—4 of Fig. 2, and

Fig. 5 is a like view on the line 5—5 of 45 Fig. 1.

In the drawings, 10 indicates the frame of the machine comprising a skeleton top plate 11 supported on vertical legs 12 that extend downwardly to the ground. Secured 50 on the top plate 11 are two bearing boxes 13 and 14 in substantially the central line of

the machine and designed to serve as bearings for a main horizontal driving shaft 15 on which is secured a pulley 16 driven in the well-known manner by a belt from a prime mover, not shown. Also keyed on the shaft 15 at its forward end and on the outside of the frame 10 is a disk 17, the outer face of which is flat and lies in a vertical plane.

The bearing box 14 has a reduced outward extension 18 threaded exteriorly at 19 and provided inwardly from its end with a cavity 20 into which the rear end of shaft 15 extends. The cavity 20 also contains an antifriction thrust bearing 21 that is maintained in place by a cap 22 having a reduced portion 23 of polygonal cross section to permit the application of a wrench when it is desired to remove, or to screw the cap upon the extension 18. To provide endwise adjustment for the shaft 15, whereby the disk 17 is caused to move to and from the frame 11, there is threaded in the cap 22 a screw stem 24 on the outer end of which is a hand wheel 25 for rotating said stem, the inner end of which is in contact with the thrust bearing 21. After adjustment has been attained, the screw stem 24 is locked in position by a nut 26.

Projecting forwardly from the top plate 11 of the frame 10 are two horizontal arms 27, 27^a, the outer ends of which have mounted thereon bearing boxes 28, 28^a for a horizontal shaft 29 lying perpendicular to shaft 15 and in the same plane. Fixed on one end 30 of shaft 29 exterior of the bearing 28^a is a belt wheel 30 for conveying power to any machine to be driven. A collar 31 is fastened to the shaft 29 on the inner side of the bearing 28^a and in connection with the belt wheel 30 prevents said shaft from moving longitudinally in its bearings. Carried by the shaft 29 between the bearings 28, 28^a and adapted to slide on said shaft across the face of the disk 17 is a friction pulley 32, the hub 33 of which is provided with a key adapted to slide in a key seat 34 extending the length of the shaft between its bearings. The pulley 32 has a central periphery or rim 35 of rubber or other suitable friction material 36 secured between side disks 36 bolted together and to the friction rim 35.

Movement of the pulley 32 on the shaft 29 is effected by means of a hand lever 37 pivoted at its lower end 38 to one of the legs 12 and extending upwardly into a suitable position to be grasped by the hand of the 40 45 50 55 60 65 70 75 80 85 90 95 100 105 110

operator. A connecting link 39 extends from the lever 37 to the hub 33 of the friction pulley 32 where it divides or forks as at 40 and extends downwardly on each side of 5 a collar 41 rotatable in a groove in the hub 33. The connecting rod or link 39 pivotally connected to said collar will, when the lever is moved toward the frame 10, carry the pulley 32 longitudinally on the shaft across 10 the flat face of the disk 17 from the circumferential edge of said disk toward the center thereof, thereby causing a reduction in the speed of rotation of the pulley 32 and shaft 29, and, if the pulley be carried beyond 15 the center of the disk 17, a reverse rotation to be given said pulley. A sliding rod 42 is connected to the bifurcated end of the link 39 and extends outwardly across the top of the adjacent portion of the top plate 20 11, passing through a bearing 43 thereon in which is threaded a clamping screw 44 that will engage the rod 42 when turned downwardly and lock said rod, thus holding the pulley 32 in any position of adjustment into 25 which it may be moved.

In using this device the prime mover is belted to the pulley 16 for rotating the shaft 15 and disk 17 at constant speed. The machine to be driven receives power 30 through the belt pulley 30 on the shaft 29, the friction pulley 32 on said shaft being in contact with the disk 17. If high speed is to be transmitted through the pulley 30 the friction pulley 32 is moved from the 35 center of the disk toward the periphery by rocking the lever 39 until a point has been reached on said disk that imparts the proper speed to the pulley 30. The clamping screw 44 is then turned to lock the rod 42 and thus 40 hold the friction wheel in the desired position. When slower speed is demanded, the friction pulley 32 is moved toward the axis

of the disk until the center thereof is reached, whereupon rotation of the pulley will cease. Further, movement of the pulley 45 in the same direction will carry it to the opposite side of the disk axis and rotate the pulley in the opposite direction, thereby obtaining reverse rotation of the pulley 30 when such is desired. Friction between the 50 disk 17 and pulley 32 is governed by the screw stem 24 at the rear end of the shaft 15 which turned in one direction forces the shaft 15 forwardly and causes the disk to press with greater force against the pulley 55 32, and when the screw stem is moved in the opposite direction necessarily this pressure is reduced.

What I claim is:

A changeable speed mechanism including 60 two shafts supported at right angles to each other, a frictional disk on one of said shafts, a frictional pulley on the other shaft engageable with said frictional disk and movable longitudinally on its shaft to and 65 from the center of the frictional disk, and means for longitudinally moving said frictional pulley, locking means for holding the pulley in a determined position comprising 70 a rod secured at one end to said means and lying parallel with the pulley shaft, a bearing mounted on a fixed support through which said rod is adapted to slide, and a screw threaded in said bearing and adapted 75 to be clamped against said rod to hold it immovable and the friction pulley in its adjusted position with relation to the friction disk.

In testimony whereof I affix my signature in presence of two witnesses.

EBENEZER S. WATERMAN.
